UNITED STATES PATENT OFFICE.

HARRY L. FELIO, OF ZION CITY, ILLINOIS.

ARTIFICIAL HAND.

No. 806,126.

Specification of Letters Patent.

Patented Dec. 5, 1905.

Application filed January 4, 1905. Serial No. 239,667.

To all whom it may concern:

Be it known that I, HARRY L. FELIO, a citizen of the United States, residing at Zion City, in the county of Lake and State of Illinois, 5 have invented a new and useful Artificial Hand, of which the following is a specification.

My invention relates to improvements in artificial hands in which the joints of the fingers and thumb are connected, by means of connecting-rods, to the mechanism in the center of the hand, which mechanism is operated by a turning of the forearm; and the objects of my invention are, first, to provide a 15 hand that is able to hold an ax or other implement so tightly that the artificial hand can be used in the same way as a natural hand to chop wood or do other manual labor; second, to afford facilities for the proper attachment 20 of the fingers and thumb to different-shaped articles; third, to afford facilities to regulate the position of the hand in reference to the wrist and forearm; fourth, to provide a hand that is light and, on the other hand, strong 25 enough so that it cannot be easily injured or broken. I attain these objects by the mechanism illustrated in the following drawings, in which—

Figure 1 is a front view of the mechanism 30 with the top or outer surface of the hand and fingers removed, looking at the palm of the hand. Fig. 2 is a side view of the worm-gear in place against the rotating disk. Fig. 3 is a side view of the worm-gear out of gear. 35 Fig. 4 shows the ratchet for manipulating the worm-gear. Fig. 5 is a side view of the standard supporting the shaft, showing the pinion-wheel and rack. Fig. 6 is a side view of the hand and thumb with the outer covering removed. Fig. 7 is a side view of the thumb 40 and forefinger when the thumb is closed over the finger. Fig. 8 is a back view of the thumb, showing its connection with the hand. Fig. 9 is a side view of the irons connecting the 45 thumb to the hand. Fig. 10 is a view of the interior mechanism of the hollow wrist-ball. Fig. 11 is a side view of the thumb and first finger when touching each other. Fig. 12 is a side view of the spring in the rods connecting 50 the thumb to the mechanism of the hand itself. Fig. 13 shows the attachment of the artificial hand to the forearm and arm.

Similar letters refer to similar parts throughout the several views.

55 The fingers consist of aluminium or wood, shaped in the form of a finger, but divided

into two sections, each section having a thin steel plate running down its center, as shown in Fig. 1.

The steel plate A in the first section of the 60 finger is connected with the steel plate or hand-iron C in the hand itself by the link D, as shown in Fig. 6. The steel plate B in the second section of the finger is connected to the steel plate A in the first section by a rivet 65 X and to the hand-iron C by a similar rivet X and is also connected with the mechanism in the center of the hand by the connecting-rod E, as shown in Figs. 1 and 6. All four fingers are similarly constructed and similarly 70 connected, with the exception that the length of the fingers are proportionate in length to the fingers of a natural hand, as shown in Fig. 1.

The four connecting-rods E are connected 75 to the iron axle or shaft F, as shown in Fig. 1. The shaft F runs through a rotating disk G, as shown in Fig. 6, the shaft being firmly fastened in the disk. In the rotating disk G is firmly fastened the axle H, which axle H is 80 set in two standards I and I, firmly fastened to the hand-iron C, as shown in Fig. 1. Attached to the standards I and I and pressing at the other end against the shaft F is the spring J, as shown in Figs. 6, 7, and 11, which 85 causes the fingers to become straight when the rotating disk G is disconnected with the worm-gear D D, as shown in Fig. 3.

Just below the worm-gear on the shaft B B the standard F F has an opening G G, as shown 90 in Fig. 5, made in an oval shape, so as to allow the shaft B B to move up and down, but not sideways. The axle H of the rotating disk G has at one end a crank K, into a hole W near the outer extremity of which is attached the 95 connecting mechanism of the thumb, as shown in Figs. 1 and 6.

The thumb consists of three sections, the outer surface being composed of aluminium or 100 wood shaped to resemble a natural thumb, with steel plates arranged in the center of each section similar to the steel plates arranged in the center of the sections of the fingers. The steel plate S in the second section of the thumb is connected to the steel plate T in the first 105 section by a rivet X and is similarly connected to the steel plate R in the third section by a rivet X, as shown in Figs. 6 and 8. The steel plate T is also connected with the steel plate R by the link P, and the steel plate S is 110 connected by the link O with the forging Q, an angle-shaped piece of steel or iron, which

in turn is connected by the bolt and spring V to the steel plate U, a thin plate of steel or other metal, which crosses the inside or palm of the hand, as shown in Figs. 6, 8, and 9.

5 In the forging U are three holes or indentations, as shown in Figs. 6 and 8, into which fits a slight knob or projection made on the forging Q. By lightly pressing up under the first section T of the thumb and at the same time bearing down on the top of the second section S of the thumb the forging Q is lifted from the forging U at the point where the projection is, the spring V giving so as to permit this, and the forging Q can be then revolved or rotated on the bolt V, so as to cause the projection on Q to slip into a different hole in the forging U. When the projection on Q is in the hole farthest from the center of the hand, the thumb is raised from the palm of the hand and will close over or outside of the fingers, as shown in Fig. 7. When the projection on Q is in the center hole, the thumb when closed will just meet with the end of the forefinger, as shown in Fig. 11. When the projection is in the hole nearest the palm of the hand, the thumb is thrown out and the thumb is in the position of a natural thumb when at rest, as shown in Fig. 1.

The third section R of the thumb is also connected to the crank K of the rotating disk G by the connecting-rod N, having a knuckle, which knuckle is inserted in a small hole W in the steel plate R, as shown in Figs. 1 and 6, and is at the other end attached to the spring M, forming a swivel with the connecting-rod L, as shown in Fig. 12. The connecting-rod L at the other end is connected with the crank K by means of a knuckle, which fits into a small hole W in crank K, as shown in Figs. 1 and 6. By means of this connecting mechanism the operator is enabled to place the thumb in several different positions.

The thumb has but three positions—to wit, (a) the extended or natural position, as when the thumb is lying opposite to and parallel with the index-finger, as when the hand is at rest; (b) when the entire thumb, excepting the fulcrum thereof, is thrown toward the palm of the hand to meet the extremities of the fingers when the hand is closed, as when used in picking up small articles, and may be thus operated in holding a pen while writing; (c) when the entire thumb, except the fulcrum thereof, is thrown toward the palm of the hand, as in (b), only the extremity is raised higher and joins on the outer side of the fingers, as when the hand is closed, and may be thus used in grasping larger articles.

The rotating disk G is operated by means of a worm-gear D D, firmly fixed on the shaft B B, as shown in Figs. 6 and 7. The shaft B B is attached at its upper end to the steel plate or hand-iron C by the standard A A, as shown in Figs. 1, 6, and 7. To the shaft B B is also attached the spring C C, as shown in Figs. 6

and 7, the tension of which pulls the worm-gear D D away from the rotating disk G, when the disk J J, by means of twisting the forearm to the extreme left, is turned with its flat side K K against the steel plate or hand-iron C, as shown in Figs. 3 and 4.

On the shaft B B, below the worm-gear D D, is the pinion-wheel E E, which pinion-wheel E E gears with the rack H H, firmly attached to the standard F F, as shown in Fig. 5, when the worm-gear D D is disconnected from the rotating disk G, which rack and pinion-wheel give the shaft B B a rotating motion when it is put into gear and a backward motion when the worm-gear is thrown out of gear, its purpose being to slacken the strain on the fingers before throwing them out of gear.

Below the standard F F the shaft B B terminates in the small wheel I I, as shown in Fig. 4. The small wheel I I is set into the disk J J, which has a flat side K K, as shown by the dotted line in Figs. 2 and 3. On the upper side of the disk J J are two pawls L L and L L, as shown in Fig. 4. The pawls L L are held against the friction or small wheel I I by the springs M M and M M, as shown in Fig. 4. The small friction-wheel I I is held in the wheel J J by two clutches N N and N N, as shown in Fig. 4.

When the disk J J, with its flat side K K, as shown in Fig. 4, is against the hand-iron C, it causes the shaft B B and the worm-gear D D to fall away from the rotating disk G, as shown in Fig. 3, and thus throws in turn the gear out when the spring J causes the disk G to rotate, so that the fingers and thumb assume an open position. Into the disk J J fastens the shaft P P, which passes through the standard O O and terminates in the knuckle Q Q, as shown in Figs. 1 and 6. The knuckle Q Q fits into a similar knuckle Q Q of the shaft R R.

The hand-iron C and the mechanism connected therewith is inclosed by an outer covering of aluminium or wood, which outer covering is made in the shape of a natural hand save that an opening is left in the upper palm of said artificial hand for the rod L to pass, connecting the thumb mechanism with the mechanism in the center of the hand, as above described. Across the upper and outer surface of the palm of said artificial hand is firmly fastened the steel plate U, as above described.

Bolted firmly to the hand-iron C at the lower extremity by rivets is a horseshoe-shaped iron S S, the lower end of which terminates in a hollow ball T T, as shown in Figs. 1 and 6. The ball T T consists of a lower piece firmly attached to the horseshoe-shaped iron S S, and the upper part of the hollow ball is connected with the lower part by means of a bolt X X, as shown in Fig. 6, through the middle of which bolt runs the shaft R R, as shown in Fig. 10.

The bolt X X may be fastened at either end in the arm-irons W W and W W, so that it

turns with them: Fastened to the bolt X X above and below where the shaft R R passes through the bolt X X are the spring-stops V V and V V, as shown in Fig. 10. On the inside 5 of the hollow ball T T are the brackets A A A and A A A, as shown in Fig. 10. The springs Y Y and Y Y are attached to the bolt X X, respectively, above and below the opening for the shaft R R, and the other ends of such 10 springs are so fixed as to strike against the brackets A A A and A A A, respectively.

By means of the spring-stops V V and V V the respective springs are prevented from 15 opening too far, and when the hand is rotated to the right the left spring will bring it back to a straight position. If it is desired to keep the hand turned at the wrist, either to the right or left position, the lever Z Z, acting as a wrench, can be turned and the nut tightened 20 on the bolt X X, thus holding the hand in the desired position.

Where the bolt X X passes through the arm-irons W W and W W, respectively, the openings may consist of a slotted hole in each, the 25 slots being parallel to the shaft R R. The springs are arranged, respectively, on either side of the bolt X X, so as to bring the hand back to the natural or straight position when it has been bent downward or upward.

30 The shaft R R, after passing through the opening of the bolt X X terminates into a knuckle Q Q, which fits into a similar knuckle Q Q of the shaft Y, which shaft is connected with the forearm by a screw and nut Z.

35 Connecting with the hollow ball T T are the steel arm-irons W W and W W, which are firmly fastened to the hollow balls T T by the bolt X X, as shown in Fig. 6.

The arm-piece U U, to which is attached the 40 shaft Y, is composed of iron, steel, or other suitable material and is made in the form of a clevis, so as to fit the flat sides of the arm. The said arm-piece is kept in place upon the stump of the natural arm by means of a leather 45 covering, which is riveted or attached to said clevis-shaped arm-piece and fastened to the natural stump of the arm by means of lacing on one side, as shown in Fig. 13.

The arm-irons W W and W W may have a 50 lap-joint at the elbow and are fastened to the upper arm by a leather covering and lacing, as shown in Fig. 13.

I am aware that previous to my invention 55 artificial hands have been constructed where the joints of the fingers are joined together by bars and the mechanism regulated by ropes attached to the shoulder or otherwise, so that I do not claim the invention of artificial hands broadly; but

60 What I do claim as my invention, and desire to secure by Letters Patent, is—

1. An artificial hand consisting of a main section, four fingers and the thumb, all of which parts are composed of thin plates of 65 steel, iron or other suitable material, to which

all the mechanism for operating the fingers and thumb are attached, the fingers being divided into two or three sections or joints, and the thumb into three sections or joints having aluminium, wood, or other suitable material 70 riveted to each side of the plates to stiffen the plates and also to shape the hand and fingers so as to resemble a natural hand, all arranged substantially as shown and described.

2. An artificial hand in which the thumb 75 and fingers, by means of cross-links between alternate sections thereof, and by means also of connecting rods or links, are connected with a worm-gear, arranged in the hollow of the hand, which worm-gear is connected with, 80 and wholly operated by the movement of the forearm, all arranged substantially as shown and for the purposes set forth.

3. An artificial hand in which the thumb is attached to the palm of the hand, by an angle-shaped piece of iron, steel or other suitable material, one side of which is bolted to the third or lower section of the thumb, and the other side of which is fastened by means of a bolt and spring, and held in different positions 85 by a knob or pin projecting from the lower side of this angle-shaped piece, fitting into holes or indentations in the bar or plate of steel, iron or other material, which crosses the upper surface or palm of the hand, by 90 which means the thumb may be placed in three or more positions, all substantially as shown and for the purposes described.

4. An artificial hand having at a joint corresponding with the wrist of the natural hand, 95 a hollow steel or iron ball to the upper and lower sides of which are attached irons from the upper arm, the ends of which are cupped so as to fit over the top of the hollow ball, and which are secured to the ball by means of a 100 bolt, which bolt has a hollow or opening in its center, to allow the shaft connecting the worm-gear with the forearm to pass through, to which bolt is also attached, on opposite sides of said opening, springs to bring the 105 hand to its natural position after being moved either to the right or to the left all substantially as shown and for the purposes described.

5. An artificial hand having in the wrist-joint a hollow steel or iron ball to which is 110 attached, on opposite sides, irons from the upper arm, in which arm-irons are slotted holes, through which a bolt connecting the irons to the hollow ball passes, and springs bearing against the bolt so as to bring the 115 hand into a straight position when moved up or down toward the palm or back, all substantially as shown and for the purposes described.

6. An artificial hand having connecting rods 120 or links from the finger or thumb attached to a rotating disk, to which is attached a spring to cause the fingers to open, which disk is regulated by a worm-gear attached to a shaft, which in turn is operated by means of a disk, 130

circular in shape, having one side cut away, which disk is connected by means of a shaft with the forearm, so that a turn of the forearm will turn the worm-gear, and cause the 5 rotating disk to close in or open the fingers as desired, all substantially as shown, and for the purposes described.

In testimony whereof I have signed my name to this specification in the presence of two subscribing witnesses.
